UNITED STATES PATENT OFFICE

2,217,674

PORTABLE DRILL RIG

John C. Curtis, Claremont, N. H., assignor to
 Sullivan Machinery Company, a corporation of
 Massachusetts

Application May 5, 1938, Serial No. 206,194

13 Claims. (Cl. 255—51)

This invention relates to portable drill rigs, and more particularly to an improved portable drill rig for a hammer rock drill whereby the latter may be supported through a wide range of drilling positions with respect to the work and readily transported from place to place.

An object of this invention is to provide an improved portable drill rig. Another object is to provide an improved portable drill rig for a hammer rock drill whereby the latter may be supported through a wide range of drilling positions. A further object is to provide an improved portable drill rig which is not only simple in design and light in weight, but is also extremely rugged and durable in construction. Yet another object is to provide an improved portable drill rig for a hammer rock drill, wherein a swinging boom structure having a swivel drill mounting at its outer end is employed for supporting the drill, the boom structure having novel means for swinging the same into and for locking it in its different adjusted positions. A still further object is to provide improved fluid supply means for the drill hammer motor, associated with the boom structure, an element of the latter providing a constant pressure chamber through which motive fluid flows to the motor. Another object is to provide a novel arrangement of the boom structure on the carriage of the drill rig whereby the drill hammer motor is rigidly supported in drilling position irrespective of the adjusted position of the boom structure. These and other objects and advantages of the invention will, however, hereinafter more fully appear.

In the accompanying drawings there is shown, for purposes of illustration, one form which the invention may assume in practice.

In these drawings—

Fig. 1 is a plan view of a drill rig constructed in accordance with an illustrative embodiment of the invention and showing a drill hammer motor mounted in drilling position thereon.

Fig. 2 is a side elevational view of the drill rig shown in Fig. 1.

Fig. 3 is an enlarged view in central longitudinal vertical section, taken substantially on line 3—3 of Fig. 1, with parts shown in elevation to facilitate illustration.

Fig. 4 is a transverse vertical sectional view taken substantially on line 4—4 of Fig. 3.

Fig. 5 is an enlarged detail sectional view taken on line 5—5 of Fig. 3.

Fig. 6 is an enlarged detail vertical sectional view taken on line 6—6 of Fig. 2.

Fig. 7 is an enlarged detail vertical sectional view taken on line 7—7 of Fig. 1.

Fig. 8 is a diagrammatic elevational view showing the drill rig in a "breast" drilling position.

Fig. 9 is a diagrammatic view in end elevation showing the drill rig in vertical drilling position.

Fig. 10 is a diagrammatic plan view showing the drill rig in a position to drill vertical "broach" holes.

Fig. 11 is a diagrammatic view in side elevation showing the drill rig in a "snake" hole drilling position.

Fig. 12 is a diagrammatic view in side elevation showing the drill rig in a position to drill a "snake" hole near the ground level.

Fig. 13 is a diagrammatic plan view showing the drill rig in a position for drilling horizontal "broach" holes.

In this illustrative embodiment of the invention, there is shown a portable drill rig for a hammer rock drill, comprising a carriage frame or chassis 1 supported at one end by a pair of wheels 2 and at the opposite end by a swiveled caster wheel 3, the wheels preferably having pneumatic tires. Attached to the caster wheel 3 is a conventional tow bar 4. The carriage frame or chassis 1 has tubular side members 5, 5 diverging outwardly and united at their adjacent ends by an upright frame 6, herein of inverted U shape and having a top cross bar 7 rigidly braced with respect to the side members 5 by bracing webs 8. Secured to the vertical side arms 9, 9 of the frame 6 and extending transversely therebetween beneath the top cross bar 7, is a frame 10 (see Fig. 4), and this frame has a vertical bearing 11 for a swivel frame 12 of the caster wheel 3. The side members 5 of the carriage frame are laterally braced by a transverse tubular member 13 extending beneath the side members and secured at its ends within depending brackets 14 rigidly fixed to the side members 5. The widely spaced ends of the diverging side members of the carriage frame have secured thereto brackets 15, and swivelly mounted on these brackets are frames 16 carrying the wheels 2 and having vertical shafts 17 (see Fig. 7) journaled within the brackets 15. Each of these brackets 15 has a pair of holes 18 adapted to register with a corresponding hole in each of the frames 16, and locking pins 19 are insertible in the registering holes for rigidly locking the frames 16 in either of two positions. Due to the pivotal connection of the wheeled frames 16

5

55

with the brackets 15, the wheels 2 may be turned about the axes of the vertical shafts 17 from the position shown in Fig. 1 through substantially 90°, into the position shown in Figs. 10 and 13, 5 and rigidly locked in position by the locking pins 19. This enables the carriage, when the 10 caster wheel is turned into the position shown in Figs. 10 and 13, to be moved laterally instead of longitudinally, a feature desirable in accomplishing certain drilling operations, as will later 15 be explained. Slidably mounted on the side members 5 of the carriage frame, between the transverse member 13 and the end frame 6, are the clamps of brackets 20 for adjustable anchor pins 21 whereby the carriage frame may be held steady during the drilling operation. These anchor pins are adjustably mounted in swivel members 22 and may be clamped in adjusted position by setscrews 23.

20 In this illustrative construction, pivotally mounted at 24 in a relatively high position on the top cross bar 7 of the end frame 6 midway between the side members 5 of the carriage frame, is an elongated boom 25, the swivel mounting at 24 being in the form of a clamp 26 which may be tightened, if desired, to hold the boom in its different adjusted positions about its pivot axle. The boom 25 is swingable upwardly and downwardly in a vertical direction 25 about its swivel mounting on the cross bar 7, and the boom-swinging means comprises a non-rotatable screw 27 pivotally connected at 28 to depending flanges 29 integral with a bracket 30 secured to the outer end of the boom. 30 Threadedly engaging at 31 the screw 27, is a rotatable nut 32 journaled in a frame 33 swiveled at 34 in a relatively low position on the cross member 13 midway between the side members of the carriage frame, this frame 33 constituting in 35 part a tubular sleeve-like portion through which the screw 27 extends, as shown in Fig. 3. Formed on the nut 32 is a worm wheel 35 (see Fig. 5) with which meshes a worm 36 fixed to a transverse shaft 37, herein suitably journaled within the frame 33. Fixed to the worm shaft 37 is a 40 handle 38 whereby the nut may be rotated through the worm gearing. By manipulating the handle 38 the boom 25 may be swung, through the worm gearing and screw and nut mechanism, in a vertical direction about its pivot into any desired position between that shown in Fig. 8 and that shown in Fig. 12. The boom clamp 26 and frame 33 are slidably mounted 45 on the top cross bar 7 and transverse member 13 respectively, for lateral adjustment relative thereto, thereby enabling the boom 25 to be located at different positions between the sides of the carriage.

Now referring to the swivel mounting at the 50 outer end of the boom, it will be noted that the frame 30 has a transverse bore 39 opening at its ends within conical sockets 40 and 41 at the opposite sides of the frame. Arranged in the frame bore is the cylindrical portion 42 of a 55 swiveled support 43, the latter having a conical portion 44 fitting the socket 41. Positioned in the opposite socket 40 is a conically-shaped clamp member 45, and a bolt 46 extends through openings in the support and clamp member whereby 60 the portion 44 and the clamp member 45 may be drawn toward one another within their sockets, frictionally to clamp the parts tightly in position. The swiveled support 43 has a laterally offset 65 conical socket 47 arranged at right angles to the sockets 40 and 41, for receiving a conical por-

tion or swivel trunnion 48 of a drill support 49. Opening into the socket 47 in the swiveled frame 43 is a bore 50 within which projects a cylindrical portion 51 of the drill support 49, and arranged in an opening in the latter is a bolt 52 engaging a 5 clamping plate 53, the latter in turn engaging an outer surface 54 of the support 43, as shown in Fig. 6. When the bolt 52 is tightened, the 10 conical portion 48 of the drill support is drawn tightly within the socket 47, frictionally to clamp 15 the drill support 49 in position on the swiveled support 43. It will thus be seen that the drill support may be swiveled about rectangularly related axes relative to the boom, and firmly clamped in adjusted position. 15

In this illustrative construction, the drill support 49 has fixed thereto a pair of parallel tubular guides 55, 55 integrally united therewith, these guides herein in the form of feed cylinders containing feed pistons having rearwardly extending piston rods 56. Slidably guided on the tubular guide members 55 is a drill hammer motor, generally designated 57, for percussively actuating a drill steel 58 in the manner well known to those skilled in the art. The piston rods 56 are connected at their rear ends by a transverse member 59; and a rod 60, arranged parallel with and between the piston rods, connects this transverse member with the rear end of the hammer motor so that when the feed pistons are moved within the feed cylinders the hammer motor is slid longitudinally relative to the guide members 55 to effect feed of the drill steel toward and from the work. A conventional drill steel centralizer 61 is mounted at the forward ends of the guide members 55 in the manner shown in Figs. 1 and 2, for guiding the drill steel during "spotting" of a hole. The hammer motor 57 is of the conventional pressure-fluid-actuated reciprocating piston type, and 40 is provided with a throttle valve mechanism 62 for controlling the supply of motive fluid to the motor to effect reciprocation of the hammer piston and to the feed cylinders to effect reciprocation of the feed pistons. In this instance, a portion 45 of the boom structure constitutes an element of the fluid supply means for the hammer motor; and to afford this the boom 25 is of tubular form and has formed therein a constant pressure chamber 63 to one end of which pressure fluid 50 may be supplied through a pipe connection 64. The opposite end of the constant pressure chamber 63 is connected by a flexible hose connection 65 to the throttle valve mechanism 62 of the drill hammer motor and feed cylinders. It will 55 thus be seen that pressure fluid flows to the hammer motor and feed cylinders from the pipe connection 64 through the constant pressure chamber 63 in the boom, and thence through the flexible hose connection 65 to the throttle valve mechanism. The constant pressure chamber obviates pressure fluctuations in the supply line leading to the motor cylinder intake, in a well known manner. The feeding structure and hammer motor disclosed herein may be similar 60 to those disclosed in the patent to M. C. Huffman, No. 2,015,678, patented Oct. 1, 1935. It will be evident that various types of feeding means may be employed in lieu of that disclosed, as, for instance, an automatic feeding mechanism of the 65 type disclosed in my copending application Serial No. 192,902, filed Feb. 28, 1938.

The general mode of operation of the improved drill rig is as follows. The drill rig may be towed 70 from one working place to another by the tow bar 75

4, the wheeled chassis providing a mobile base whereby the rig may be readily moved over the ground surface. When it is desired to drill horizontal "breast" holes in the working face, the 5 drill rig may be positioned in a manner shown in Fig. 8, with the boom 25 swung upwardly to support the drill hammer motor 57 in a relatively high horizontal drilling position. The anchor pins 21 may then be adjusted into engagement 10 with the floor to steady the drill. Motive fluid may then be supplied to the hammer motor, under the control of the throttle valve mechanism 62, through the pipe connection 64, the constant pressure chamber 63 in the boom 25, and the flexible hose connection 65; and as the hammer motor operates it may be fed along its guides 55, 55 also under the control of the throttle valve mechanism 62. The boom 25 may be swung in a vertical 15 direction about its swivel mounting simply by turning the handle 38 to rotate the nut 32, thereby to move the screw 27 axially relative to the nut, and the screw and nut cooperate to lock the boom in its adjusted position. By loosening the conical clamps 44 and 48, the drill support 20 may be swung in a vertical direction about a horizontal axis relative to the boom, and horizontally relative to the boom about a vertical axis, into any desired position, and thereafter may be firmly clamped in adjusted position by tightening the clamping bolts 46 and 52. By the provision of 25 the horizontal swivel at the outer end of the boom 25, the drill guide may be swung either above or below the boom, as desired. From the foregoing, it will be evident that horizontal "breast" holes 30 may be drilled in the working face at various locations without moving the carriage of the drill rig. During vertical drilling in the floor, the drill guide may be swung about its horizontal swivel relative to the boom 25, into the position shown 35 in Fig. 9. An aligned series of vertical "broach" holes may be drilled in the floor by adjusting the wheels 2 and the caster wheel 3 into the position shown in Fig. 10 and adjusting the drill guide about its horizontal swivel into the vertical position shown. When one "broach" hole is 40 completed, the hammer motor may be withdrawn upwardly from the work and the drill rig moved a short distance laterally into a new drilling position, these operations being repeated until the 45 desired series of aligned holes is obtained. During the drilling of a series of horizontal "broach" holes, the drill guide may be swung into the horizontal position shown in Fig. 13, and, with the 50 wheels in the same position shown in Fig. 10, the drill rig may be moved laterally through a series of horizontal drill-supporting positions. When it is desired to drill a "snake" hole in the 55 working face above the floor level, the boom 25 may be swung downwardly by the screw and nut mechanism, and the drill guide may be swung about its horizontal swivel into the position shown 60 in Fig. 11, with the drill guide above the boom. During "snake" hole drilling near the floor level, the drill guide is swung about its horizontal swivel 65 beneath the boom, as shown in Fig. 12. If desired, the drill guide may be swung about its vertical swivel relative to the boom to drill holes in directions extending transversely of the drill rig, and by swiveling the drill guide about both of its 70 swivel axes, holes may be drilled in various inclined positions with respect to the horizontal and vertical.

In any of the above drill-supporting positions of the drill rig, the anchor pins 21 may be adjusted into engagement with the floor to steady 75

the drill during the drilling operation, and by the provision of the adjustable clamps for the anchor pins the latter may be adjusted into various floor-engaging positions, as desired. Due to the particular arrangement of the boom and boom-adjusting means relative to the carriage, the drill guide is maintained extremely steady in all adjusted positions thereof. When it is desired to transport the drill rig from one working place to another, the wheels 2 are locked in the position shown in Fig. 1 so that when the drill guide and boom are in the position shown in Fig. 2 the drill rig may be moved longitudinally over the ground. Other uses and advantages of the improved drill rig will be clearly apparent to those skilled in the art.

While there is in this application specifically described one form which the invention may assume in practice, it will be understood that this form is shown for purposes of illustration and that the invention may be modified and embodied in various other forms without departing from its spirit or the scope of the appended claims.

What I claim as new and desire to secure by Letters Patent is:

1. A rock drill rig comprising, in combination, a wheel-supported carriage having side frame members and a transverse frame uniting said side frame members at one end of the carriage, a transverse bracing member extending across and connecting said side frame members substantially midway between the ends of the carriage, the opposite end of said carriage beyond said transverse bracing member being open and the space between said side frame members at said opposite carriage end being free and unobstructed, a boom pivotally mounted on said transverse frame to swing in a vertical direction relative to said carriage with its outer end disposed at said opposite end of said carriage, adjustable means connected to the outer end of said boom beneath the latter and to said transverse bracing member and extending upwardly through said space between said side frame members for swinging said boom about its pivot, and a drill support mounted at the outer end of said boom.

2. A rock drill rig comprising, in combination, a wheel-supported carriage having side frame members and a transverse frame uniting said side frame members at one end of the carriage, a transverse bracing member extending across and connecting said side frame members substantially midway between the ends of the carriage, the opposite end of said carriage beyond said transverse bracing member being open and the space between said side frame members at said opposite carriage end being free and unobstructed, a boom pivotally mounted on said transverse frame to swing in a vertical direction relative to said carriage with its outer end disposed at said opposite end of said carriage, adjustable means connected to the outer end of said boom beneath the latter and to said transverse bracing member for swinging said boom about its pivot, a drill support mounted at the outer end of said boom, said boom swinging means being adjustable to swing said boom downwardly about its pivot into a position wherein the outer end of said boom lies between said side frame members with said drill support located in said space between said side frame members at said open end of said carriage.

3. A rock drill rig comprising, in combination, a wheel-supported carriage having side frame members and a transverse frame uniting said side frame members at one end of the carriage, a

transverse bracing member extending across and connecting said side frame members substantially midway between the ends of the carriage, the opposite end of said carriage beyond said 5 transverse bracing member being open and the space between said side frame members being free and unobstructed, a boom pivotally mounted on said transverse frame to swing in a vertical direction relative to said carriage with its 10 outer end disposed at said opposite end of the carriage, adjustable means connected to the outer end of said boom beneath the latter and to said transverse bracing member and extending upwardly through said space between said side 15 frame members for swinging said boom about its pivot and for locking said boom in its adjusted position, and a drill support mounted at the outer end of said boom.

4. A rock drill rig comprising, in combination, 20 a wheel-supported carriage having side frame members and a transverse frame uniting said side frame members at one end of the carriage and having a horizontal portion arranged at a relatively high point above said side frame members, a transverse bracing member extending across and connecting said side frame members substantially midway between the ends of the carriage, said transverse member being arranged at a relatively low point beneath said side frame 25 members, the opposite end of said carriage beyond said transverse bracing member being open and the space between said side frame members at said opposite carriage end being free and unobstructed, a boom pivotally mounted on the 30 horizontal portion of said transverse frame to swing in a vertical direction relative to said carriage with its outer end disposed at said opposite end of the carriage, adjustable means connected to the outer end of said boom beneath the latter and to said transverse bracing member and extending upwardly through said space between said side frame members for swinging said boom about its pivot, and a drill support mounted at the outer end of said boom. 35

45 5. A rock drill rig comprising, in combination, a carriage frame having one end thereof free and unobstructed providing an open space, supporting wheels for said frame, a support overlying said carriage frame and mounted thereon at the opposite end of the frame for adjustment 40 in a vertical direction relative thereto, adjustable means mounted on said carriage frame and connected to the outer end of said support beneath the latter for adjusting said support in a vertical direction, a support mounted on said adjustable support at the free and unobstructed end of said carriage frame, said last mentioned support pivotally mounted on said first support to swing relative thereto about a horizontal axis, 50 a third support pivotally mounted on said second support to swing relative thereto on a vertical axis, and a drill support mounted on said last mentioned pivoted support, said first mentioned support being adjustable into a position wherein 55 its outer end lies within the open space at the free and unobstructed end of said carriage frame.

6. A rock drill rig comprising, in combination, 60 a carriage frame having one end thereof free and unobstructed providing an open space, supporting wheels for said frame, a support overlying said carriage frame and mounted thereon at the opposite end of the frame for adjustment in a vertical direction relative thereto, a support mounted on said adjustable support at 65 the free and unobstructed end of said carriage

frame, said last mentioned support pivotally mounted on said first support to swing relative thereto about a horizontal axis, a third support pivotally mounted on said second support to swing relative thereto on a vertical axis, extensible 5 means connected to said carriage frame and the outer end of said adjustable support beneath the latter and extending upwardly through said open space for adjusting said adjustable support in a vertical direction relative to said carriage frame, 10 and a drill support mounted on said last mentioned pivoted support, said first mentioned support being adjustable into a position wherein its outer end lies within the open space at the free and unobstructed end of said carriage frame. 15

7. A drill rig comprising, in combination, a carriage frame having spaced side members and a frame connecting said side members at one end of the carriage frame, said connecting frame having a transverse horizontal portion located 20 above said side members, supporting wheels for said carriage frame, a transverse bracing member connecting said side members and arranged beneath the latter, the opposite end of said carriage beyond said transverse bracing member being 25 open and the space between said side members at said opposite carriage end being free and unobstructed, a boom pivotally mounted on said transverse horizontal frame portion substantially midway between said carriage frame side members, said boom swingable about its pivot in a vertical direction relative to said carriage frame and having its outer end swingable downwardly into a position wherein its outer end lies in said space between said carriage side members at 30 said opposite end of said carriage frame, an extensible adjusting mechanism connected to the outer end of said boom beneath the latter and to said transverse bracing member and extending upwardly through said space between said side members for swinging said boom about its pivot, and a drill support carried by said boom at the outer end of the latter. 35

8. A drill rig comprising, in combination, a carriage frame having outwardly diverging side 40 members and an inverted U-shaped frame uniting the adjacent ends of said side frame members at one end of said carriage frame, said U-shaped frame having a horizontal portion disposed at a relatively high point transversely above 45 said side frame members and depending side arm portions secured to said side frame members, a frame extending transversely between said side arm portions beneath said horizontal portion, a caster wheel swivelled on said last mentioned 50 frame for supporting one end of said carriage frame, a pair of wheels for supporting the opposite end of said carriage frame, a boom pivotally mounted on said horizontal frame portion to swing in a vertical direction relative thereto 55 and having its outer end located in adjacency to said opposite end of said carriage frame, and a drill support mounted at the outer end of said boom. 60

9. A drill rig comprising, in combination, a carriage frame having outwardly diverging side 65 members and an inverted U-shaped frame uniting the adjacent ends of said side frame members at one end of said carriage frame, said U-shaped frame having a horizontal portion disposed at 70 a relatively high point transversely above said side frame members and depending side arm portions secured to said side frame members, a frame extending transversely between said side arm portions beneath said horizontal portion, 75

5 a caster wheel swivelled on said last mentioned frame for supporting one end of said carriage frame, a pair of wheels for supporting the opposite end of said carriage frame, a boom pivotally mounted on said horizontal frame portion to swing in a vertical direction relative thereto and having its outer end located in adjacency to said opposite end of said carriage frame, a transverse member extending between and connecting said carriage side members and arranged beneath the latter, adjustable means connected to the outer end of said boom beneath the latter and to said transverse member for swinging said boom about its pivot, and a drill support mounted 15 at the outer end of said boom.

10 10. A rock drill rig comprising, in combination, a wheel-supported carriage having side frame members and a transverse frame uniting said side frame members at one end of the carriage, a transverse bracing member extending across and connecting said side frame members substantially midway between the ends of the carriage, the opposite end of said carriage beyond said transverse bracing member being open and the 15 space between said side frame members being free and unobstructed, a boom pivotally mounted on said transverse frame to swing in a vertical direction relative to said carriage with its outer end disposed at said opposite end of the carriage, adjustable means connected to said boom beneath the latter and to said transverse bracing member and extending upwardly through said space between said side frame members for swinging said boom about its pivot, said boom and boom 20 adjusting means being slidable relative to said transverse frame and said transverse bracing member into different laterally located positions on the carriage, and a drill support mounted at the outer end of said boom.

25 11. A drill rig comprising, in combination, a carriage frame having spaced side members and a frame connecting said side members at one end of the carriage frame, said connecting frame having a transverse horizontal portion located above said side members, supporting wheels for said carriage frame, a transverse bracing member connecting said side members and arranged beneath the latter, the opposite end of said carriage beyond said transverse bracing member being open and the space between said side members at said opposite carriage end being free and unobstructed, a boom pivotally mounted on said transverse horizontal frame portion substantially midway between said carriage frame side members, said boom swingable about its pivot in a vertical direction relative to said carriage frame and having its outer end swingable downwardly into a position wherein its outer end lies in said space between said carriage side members at said 30 opposite end of said carriage frame, an extensible adjusting mechanism connected to the outer end of said boom beneath the latter and to said transverse bracing member and extending upwardly through said space between said side members for swinging said boom about its pivot, said boom and said extensible adjusting mech-

anism being slidable along said transverse horizontal portion and said transverse bracing member into different laterally located positions on the carriage frame, and a drill support carried at the outer end of said boom.

5 12. A rock drill rig comprising, in combination, a wheel-supported carriage having side frame members and a transverse frame uniting said side frame members at one end of the carriage, a transverse bracing member extending across and connecting said side frame members substantially midway between the ends of the carriage, the opposite end of said carriage beyond said transverse bracing member being open and the space between said side frame members being 10 free and unobstructed, a boom pivotally mounted on said transverse frame to swing in a vertical direction relative to said carriage with its outer end disposed at said opposite end of the carriage, adjustable means connected to the outer end of said boom beneath the latter and to said transverse bracing member and extending upwardly through said space between said side frame members for swinging said boom about its pivot and for locking said boom in its adjusted position, 15 and a drill support mounted at the outer end of said boom, said boom swinging means being adjustable to swing said boom downwardly into a position wherein its outer end lies between said side frame members with said drill support located in said space between said side frame members at said open end of said carriage.

20 13. A rock drill rig comprising, in combination, a wheel-supported carriage having side frame members and a transverse frame uniting said side frame members at one end of the carriage and having a horizontal portion arranged at a relatively high point above said side frame members, a transverse bracing member extending across and connecting said side frame members 25 substantially midway between the ends of the carriage, said transverse member being arranged at a relatively low point beneath said side frame members, the opposite end of said carriage beyond said transverse bracing member being open and the space between said side frame members at said opposite carriage end being free and unobstructed, a boom pivotally mounted on the horizontal portion of said transverse frame to swing in a vertical direction relative to said carriage with its outer end disposed at said opposite end of the carriage, adjustable means connected to the outer end of said boom beneath the latter and to said transverse bracing member and extending upwardly through said space between said side frame members for swinging said boom about its pivot, and a drill support mounted at the outer end of said boom, said boom swinging means being adjustable to swing said boom 30 downwardly into a position wherein its outer end lies between said side frame members with said drill support located in said space between said side frame members at said open end of said carriage.

35 J. C. CURTIS. 65
